UNITED STATES PATENT OFFICE.

MILTON M. SWEENEY, OF PITTSBURG, PENNSYLVANIA.

LEGGIN.

SPECIFICATION forming part of Letters Patent No. 373,788, dated November 22, 1887.

Application filed August 13, 1887. Serial No. 216,884. (No model.)

To all whom it may concern:

Be it known that I, MILTON M. SWEENEY, a citizen of the United States, residing at Pittsburgh, in the county of Allegheny and State of Pennsylvania, have invented certain new and useful Improvements in Leggins; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of this invention, and shows a perspective view of a leggin opened so as to show all the fastenings. Fig. 2 is a vertical section through the two edges of the leggin when fastened together. Fig. 3 is a detail and a perspective view.

The invention relates to improvements in leggins, referring more particularly to the fastenings of the same; and it consists in the construction and novel combination of parts, as hereinafter described.

Referring to the accompanying drawings by letters, A designates a piece of suitable material—such as canvas, leather, or rubber—forming the web of the leggin, and B B' are sockets stitched or otherwise secured to the outer surface of one edge of the web near the upper and lower ends thereof, the upper socket opening downward and the lower socket opening upward. The sockets B B' are formed from a single piece of metal, the return-piece a being formed before the socket portion a' is stamped in the metal. The stamped plate is turned upon itself to complete the socket, which consists of the front plate, b, the rear plate, b', and the closed end c. Openings are made in the socket for the passage of a wire or other fastening material.

C is a wire or small bar of steel secured to the inner surface of the web near the opposite edge and longer than the distance between the 45 sockets.

E is a hook of suitable construction secured to the web midway between the sockets, and F is an eye secured to a corresponding point of the web between the ends of the spring-bar.

Instead of a hook and eye a button and button-hole, or other suitable fastening device, may be used.

To secure the device upon the leg the web is 55 wrapped around the same, the fastening being preferably outward, and the lower end of the spring-rod inserted in the lower socket. The rod is then bent until the upper end of said rod can enter the upper socket and let go, so 60 that it straightens itself and holds in both sockets. The central fastening device is then engaged.

The spring and sockets, besides being a quick, ready, and secure means of supporting the 65 leggins, form a support therefor, so that the device is self-supporting.

The device is cheap, effective, and easily taken off and put on.

Having described my invention, I claim— 70
In a leggin, the combination, with the spring-bar, of the socket formed from one piece of metal, and consisting of the front plate, b, the rear plate, b', and having the closed end c, the front plate being provided with the socket portion a', and reflected end adapted to engage the end of the spring-bar, substantially as 75 specified.

In testimony whereof I affix my signature in presence of two witnesses.

MILTON M. SWEENEY.
